UNITED STATES PATENT OFFICE.

CHARLES E. TWITT, OF WEST TAMPA, FLORIDA, ASSIGNOR OF ONE-HALF TO WILLIAM J. TWITT, OF WEST TAMPA, FLORIDA.

FORM FOR MAKING CONCRETE CURBS OR GUTTERS.

No. 861,686.

Specification of Letters Patent.

Patented July 30, 1907.

Application filed April 18, 1907. Serial No. 368,933.

To all whom it may concern:

Be it known that I, CHARLES E. TWITT, a citizen of the United States, residing at West Tampa, in the county of Hillsboro and State of Florida, have invented 5 a new and useful Form for Making Concrete Curbs and Gutters, of which the following is a specification.

This invention relates to molds for making concrete curbs and gutters for streets, road-ways and the like and has for its object to provide a strong, durable and thoroughly efficient mold of this character capable of being 10 readily set up for use and quickly adjusted so as to permit the formation of curbs and gutters of different widths.

A further object of the invention is to provide a mold 15 including spaced timbers having impaling pins slidably mounted thereon and adapted to be driven into the ground thereby to prevent spreading of said timbers when tamping the cement, concrete or other plastic material in the mold.

20 A further object is to provide a rectangular frame which rests on one of the longitudinal timbers and is spaced laterally from the opposite timber to form the curb or coping, there being transverse bars connecting the longitudinal timbers and operatively connected 25 with the rectangular frame for supporting the latter in position on said timbers.

A still further object of the invention is to generally improve this class of devices so as to increase their utility, durability and efficiency.

30 Further objects and advantages will appear in the following description, it being understood that various changes in form, proportions and minor details of construction may be resorted to within the scope of the appended claims.

35 In the accompanying drawings forming a part of this specification: Figure 1 is a perspective view of a mold constructed in accordance with my invention. Fig. 2 is an end view of the same. Fig. 3 is a top plan view of a portion of the mold showing the construction of the 0 connecting bars and locking cams.

Similar numerals of reference indicate corresponding parts in all of the figures of the drawings.

The improved mold forming the subject matter of the present invention includes spaced longitudinal timbers. 5 5 and 6 preferably of different heights and adapted to rest on the ground where the curb or gutter is to be formed.

Secured to the outer faces of the timbers 5 and 6 are spaced keepers or loops 7 in which are mounted for 0 vertical movement impaling pins or rods 8 each having one end thereof provided with a laterally extending head 9 and its opposite end reduced to form a pointed terminal 10 adapted to be driven or otherwise embed-

ded in the ground thereby to prevent spreading of the longitudinal timbers when tamping the concrete, cement or other plastic material between the same.

Combined with the timbers 5 and 6 is a substantially rectangular frame consisting of longitudinal bars 11 and 12 connected by transverse beams or strips 13 which rest on the timber 15 and serve to support the 60 rectangular frame in elevated position.

The longitudinal bar 12 is spaced laterally from the adjacent longitudinal timber 6 to form an intermediate molding compartment 14, the lower longitudinal edge of the bar 12 being curved or deflected laterally at 15 65 so as to give the proper curvature to the base of the curb or coping, indicated at 16.

The longitudinal timbers 5 and 6 are spaced apart by transverse bars 17 which are disposed parallel with the upper edges of the timber 6 and bar 12 and thence 70 bent downwardly and provided with lateral extensions 18 which rest upon the upper edge of the longitudinal timber 5.

One longitudinal edge of each connecting bar 17 is formed with a plurality of spaced notches or recesses 75 19 adapted to receive pins or studs 20 carried by the longitudinal timbers 5 and 6, there being cams 21 pivotally mounted on the longitudinal timbers and adapted to bear against the adjacent longitudinal edges of the connecting bars 17 for forcing the notches or 80 recesses 19 of the bars in engagement with the adjacent pins.

The pins 20 are preferably provided with enlarged heads 22 which over-lap the bars 17 so as to lock the same against vertical movement.

85

Extending vertically from the upper longitudinal edge of the bar 12 are headed pins 23 similar in construction to the pins 20 and which are forced into engagement with the intermediate recesses in the transverse bars 17 by means of cams 24 also similar in construction to the cams 21 thus serving to support the inner end of the frame in elevated position.

Attention is here called to the fact that the lower edges of the transverse beams or strips 13 are bowed upwardly at 25 so as to prevent the same from coming 95 in contact with the adjacent face of the gutter 26. In some cases suitable pins or rods 27 are extended through the transverse beams or strips 13 for engagement with the adjacent longitudinal timber 5 thereby to assist in preventing accidental displacement of the rectangular frame.

In using the mold the longitudinal timbers 5 and 6 are spaced apart the desired distance and locked in adjusted position by rotating the cams 21 after which the impaling members 8 are driven into the ground so 105 as to prevent accidental movement of the mold.

The cement, concrete or other plastic material is then shoveled into the compartment formed by the timbers 5 and 6 and said cement troweled in the usual manner to form the upper surface of the gutter 26. The 5 rectangular frame is then positioned on the timber 5 with the longitudinal bar 12 spaced laterally from the timber 6 and secured in position thereon by introducing the pins 27 and manipulating the cams 24 so as to force the bars 17 in engagement with the headed pins 10 23, the cement or concrete being subsequently introduced in the molding compartment 14 and thoroughly tamped to form the gutter 16.

In order to remove the mold it is merely necessary to 15 detach the pins 27 and move the cams to released position when the bars 17 may be removed and said frame detached from the longitudinal timbers. If desired, however, the rectangular frame may be combined with the longitudinal timbers before introducing the cement or other plastic material into the mold, as illustrated 20 in Fig. 1 of the drawings.

The upper surface of the gutter 26 may be rendered smooth or level or slightly concave, as shown in Fig. 2 so as to assist in draining the water in said gutter.

From the foregoing description it is thought that the 25 construction and operation of the device will be readily understood by those skilled in the art and further description thereof is deemed unnecessary.

Having thus described the invention what is claimed is:

- 30 1. A mold including spaced longitudinal timbers of different heights and connected by transverse bars, a stationary frame supported on the timbers and having one longitudinal edge thereof bearing against the connecting bars and spaced from and disposed in horizontal alignment with the upper longitudinal edge of the highest 35 timber to form an intermediate molding compartment, and impaling members slidably mounted on the exterior faces of the longitudinal timbers and adapted to be embedded in the ground.
- 40 2. A mold including spaced longitudinal timbers of different heights and connected by inclined transverse bars, and a stationary frame supported on the timbers and having

one longitudinal edge thereof curved laterally and spaced from the highest longitudinal timber to form an intermediate molding compartment.

3. A mold including spaced longitudinal timbers of different heights and connected by transverse bars, a stationary frame supported by the longitudinal timbers and having its inner wall curved laterally and spaced from the highest longitudinal timber to form an intermediate molding compartment, pins extending through the frame and engaging one of the timbers, and impaling members slidably mounted on the exterior faces of the longitudinal timbers and each having one end thereof provided with a pointed terminal adapted to engage the ground and its 55 opposite end formed with a driving head.

4. A mold including spaced longitudinal timbers connected by transverse bars having recesses formed therein, pins extending vertically from the timbers, and provided with enlarged heads over-lapping the adjacent transverse 60 bars and cams mounted on said timbers and adapted to bear against the bars for forcing the pins in engagement with the recesses.

5. A mold including spaced longitudinal timbers of different heights, transverse bars connecting said timbers and each having one longitudinal edge thereof provided with spaced recesses, pins extending vertically from the upper edges of the timbers and provided with enlarged heads over-lapping the adjacent transverse bars, and cams pivotally mounted on the timbers and adapted to bear against 70 the bars for locking the pins in engagement with the recesses.

6. A mold including spaced longitudinal timbers, transverse bars connecting the timbers and each having one longitudinal edge thereof provided with terminal and intermediate recesses, a frame supported by the longitudinal timbers and having its inner longitudinal edge disposed in contact with the transverse bars and spaced from one of the longitudinal timbers to form an intermediate molding compartment, pins extending vertically from the frame 8 and longitudinal timbers, respectively, and provided with enlarged heads over-lapping the adjacent transverse bars and cams carried by the timbers and frame for forcing the recessed edges of the bars in engagement with the adjacent pins.

In testimony that I claim the foregoing as my own, I have hereto affixed my signature in the presence of two witnesses.

CHARLES E. TWIFT.
